UNITED STATES PATENT OFFICE.

AUGUST G. MYERS, OF CLEVELAND, OHIO.

DESIGN FOR A BRACKET FOR LIGHTING FIXTURES.

Application filed January 23, 1926. Serial No. 16,231. Term of patent 7 years.

To all whom it may concern:

Be it known that I, AUGUST G. MYERS, a citizen of the United States, residing at Cleveland, in the county of Cuyahoga and State of Ohio, have invented a new, original, and ornamental Design for a Bracket for Lighting Fixtures, of which the following is a specification, reference being had to the accompanying drawing, forming a part thereof.

The figure is a perspective view of the bracket for lighting fixtures showing my new design.

I claim:

The ornamental design for a bracket for lighting fixtures as shown.

AUGUST G. MYERS.
